UNITED STATES PATENT OFFICE

167,731

PIN OR SIMILAR ARTICLE

Dennis Willinger, New York, N. Y.

Application January 30, 1952, Serial No. 18,293

Term of patent 3½ years

(Cl. D45—19)

To all whom it may concern:

Be it known that I, Dennis Willinger, a citizen of the United States of America, residing in New York city, county of Bronx, and State of New York, have invented a new, original, and ornamental Design for a Pin or Similar Article, of which the following is a specification, reference being had to the accompanying drawing, forming part thereof, wherein,

The characteristic features of my design reside in the portions shown in full lines in the drawing.

I claim:

The ornamental design for a pin or similar article, substantially as shown and described.

DENNIS WILLINGER.
